United States Patent Office

Des. 181,885
Patented Jan. 7, 1958

181,885

STATION WAGON

William D. Steere, Oak Park, and Carl H. Renner, Detroit, Mich., assignors to General Motors Corporation, Detroit, Mich., a corporation of Delaware

Application October 7, 1954, Serial No. 32,578

Term of patent 7 years

(Cl. D14—3)

Fig. 1 is a top perspective view of a station wagon embodying our new design;

Fig. 2 is a side elevation thereof; and

Fig. 3 is a front elevation thereof.

The dominant features of our design reside in the full line portion of the drawing.

We claim:

The ornamental design for a station wagon, substantially as shown and described.
